(57) **CLAIM**

The ornamental design for a magnetic towel, as shown and described.

DESCRIPTION

FIG. 1 is a perspective view of the magnetic towel, showing the new design;

FIG. 2 is a front elevational view of the magnetic towel thereof;

FIG. 3 is a rear elevational view of the magnetic towel thereof;

FIG. 4 is a left side elevational view of the magnetic towel thereof;

FIG. 5 is a right side elevational view of the magnetic towel thereof;

FIG. 6 is a top plan view of the magnetic towel thereof; and, FIG. 7 is a bottom plan view of the magnetic towel thereof. The broken lines show stitching on the magnetic towel that forms no part of the claimed design.

1 Claim, 3 Drawing Sheets
